(57) **CLAIM**

The ornamental design for a clip for fitness tracker, as shown and described.

DESCRIPTION

FIG. 1 is a front, top perspective view of a clip for fitness tracker according to our new design.

FIG. 2 is a rear, bottom perspective view thereof.

FIG. 3 is a top plan view thereof.

FIG. 4 is a bottom plan view thereof.

FIG. 5 is a right side elevational view thereof.

FIG. 6 is a left side elevational view thereof.

FIG. 7 is a front elevational view thereof.

FIG. 8 is a rear elevational view thereof.

FIG. 9 is a cross-sectional view taken generally along line 9-9 shown in FIG. 3; and,

FIG. 10 is a further side elevational view thereof with a fitness tracker disposed within the clip.

The broken line showing of a portion of a fitness tracker within the clip is for environmental purposes only and forms no part of the claimed design.
